CLAIM

The ornamental design for a laid back brush, as shown and described.

DESCRIPTION

FIG. 1 is a perspective view of the first embodiment of the laid back brush;

FIG. 2 is a right-hand view thereof, the left-hand elevation view being a mirror image thereof;

FIG. 3 is a bottom view thereof;

FIG. 4 is a top view thereof;

FIG. 5 is a front view thereof; and

FIG. 6 is back view thereof; and

FIG. 7 is a perspective view of the second embodiment of the laid back brush;

FIG. 8 is a right-hand view thereof, the left-hand elevation view being a mirror image thereof;

FIG. 9 is a bottom view thereof;

FIG. 10 is a top view thereof;

FIG. 11 is a front view thereof; and,

FIG. 12 is back view thereof.

1 Claim, 2 Drawing Sheets
